PACKING RETAINER

Bartholomew A. Diggins, Kensington, Md., assignor to
Stanley G. Bair, Chicago, Ill.

Application January 7, 1955, Serial No. 480,430

11 Claims. (Cl. 308—89)

The present invention relates to packing retainers or keepers and more particularly to resilient wire packing keepers.

In the ordinary waste packed railroad journal assembly, the waste tends to become displaced due to operation and impact and displacement of the waste is a common source of hot boxes. For many years efforts have been made to prevent displacement of the waste packing and numerous devices have been proposed to retain the waste in position. One class of waste keepers or retainers is formed of rather heavy steel or brass wire and while these wire retainers are rather widely used, prior to the present invention such retainers have had certain inherent and well recognized deficiencies.

One form of wire retainer is constructed so that it bears resiliently against the waste and because of the large forces tending to displace the waste when the car is subjected to impact, the resilient force is frequently inadequate to prevent waste displacement. Further, since the retainer is under compression, any displacement of the retainer itself may result in the retainer springing loose in the journal box.

Another common type of retainer has four upright legs which engage the top of the box in the four corners. While this retainer avoids some of the difficulties of the spring type retainer, it is almost impossible to remove the four-leg type of retainer without ruining it. The legs which extend up to the front top corner of the box usually engage so snugly that they can be removed only by bending or distorting them to such an extent that the retainer cannot be used again.

Both types of wire packing keeper of the prior art have utilized clips which carry most of the load or strain in the keeper and are subjected to impact caused by relative movement of the journal, brass and box. In service the clips frequently fail after a relatively short period of use thereby destroying the packing retaining function of the keeper and resulting in hot boxes. In addition the clips utilized in many keepers of the prior art have been relatively complicated and the right and left hand clips have been different. Such clips are relatively expensive to manufacture, do not eliminate the problem of clip failure, and increase assembly costs.

According to the present invention there is provided a resilient packing keeper having a three point upper engagement with the top of the journal box. The retainer is held in position independently of the waste by resilient engagement with the bottom, the upper rear corners of the box and with the opening in the wedge. The tendency of the waste to roll is transmitted to the top of the box and pressures against the retainer are transmitted to the box. The keeper has overlapping portions so arranged that vertical stress applied to the keeper is carried by these portions so that the clip merely holds the overlapped portions in position and does not receive the full applied force.

In another form of the present invention, clips are

2

eliminated entirely. The retainer bears resiliently against the bottom of the journal box and has a three-point upper suspension so that upward forces are transmitted directly to the top of the box while the retainer is resiliently fixed in position at all times. The resilient forces holding the retainer in position also urge the rear legs outwardly against the side walls of the box and away from the journal.

It is accordingly an object of the present invention to provide a simple and efficient packing keeper which will maintain its position in a railway journal box during use while holding the packing in its proper position.

It is another object of the invention to provide a packing retainer for waste-packed journal boxes which is held in position by resilient engagement with the journal box and wedge independently of the waste packing.

It is another object of the invention to provide a packing keeper which may be removed and reinserted in a journal box without distortion or damage.

It is another object of the present invention to provide a packing keeper in which the clips bear only a relatively small portion of the strain applied to the keeper.

It is still another object of the present invention to provide a simple and efficient packing keeper utilizing relatively simple clips in such a manner as to materially lengthen the life of the clips and hence of the keeper.

It is still another object of the present invention to provide a wire packing keeper having top and bottom engagement at the forward end of the journal box and rear legs for engaging the upper rear corners of the box and in which flexure of the forward portion of the keeper urges the upper ends of the rear legs into firm engagement with the side walls of the journal box.

A further object of the present invention is to provide a packing retainer in which no clips are required.

A further object is to provide a retainer for inserting lubricating pads into a journal box and retaining the pads in position.

Further objects and advantages of the invention will be apparent upon reference to the following specification and claims and the appended drawings wherein:

Figure 1 is a vertical section of a journal box showing the improved keeper of the invention in position;

Figure 2 is a front elevation of the keeper of the invention;

Figure 3 is a top view of the keeper of the invention;

Figure 4 is a vertical section of a journal box showing a modified retainer according to the invention in position;

Figure 5 is a front elevation of the retainer shown in Figure 4;

Figure 6 is a top plan view of the retainer shown in Figure 4; and

Figure 7 is a fragmentary vertical section similar to Figures 1 and 4 showing a retainer for inserting and holding a lubricating pad in position.

Referring more particularly to the embodiment shown in Figures 1 to 3 of the drawings, there is shown in Figure 1 a conventional railway journal box according to the standards and specifications of the American Association of Railroads. This journal box has a top 10, a bottom 12, side walls 14, and a hinged cover 16. The journal 18 extends into the box through an opening 20 in the rear wall 22 of the box, and the journal brass 24 rests on the journal 18. The wedge 26 is located between the brass and the top 10 of the box. The rear wall 22 of the box is provided with a slot or groove 28 for receiving an oil seal or dust guard, not shown. Waste packing 30, located in the bottom of the box, engages the lower part of the journal 18 and oil in the bottom of the box is carried up to the journal 18 through the waste by capillary action to

lubricate the journal 18. Adjacent the top 10 of the box and above the opening 20 the rear wall 22 forms an inwardly facing shoulder 32 which extends downward from the top 10 at the rear of the box and wedge stop lugs 34 project down from the top of the box 10 at the front near the upper end of the cover. The standard journal has a fillet 36 which is usually located within the box closely adjacent the inner surface of the rear wall 22 and the outer end of the journal is provided with a collar 38. The dimensions of construction of this journal assembly and associated parts conform to the standards set by the American Association of Railroads.

It is the purpose of the retainer of the present invention to hold the packing 30 in position without interference with the journal 18, journal brass 24, or wedge 26 which shift or move during operation.

The retainer illustrated in Figures 1 to 3 is formed of a single piece of resilient wire which may be of steel, brass, or other resilient metal, and may be round, square or flat. This keeper or retainer consists generally of a front leg 40, a looped rear leg 42 and horizontal packing coverage portion 44 on one side of the journal 18, and a front leg 46, loop shaped rear leg 48 and packing covering portion 50 on the other side of the journal 18. A cross piece or brace 52 extends under the journal 18 and is preferably out of alignment with the journal collar 38, and a pair of upwardly extending arms 54 and 56 attached to front legs 40 and 46 meet in vertical ends 58 and 60. The arms 54 and 56 extend upwardly, inwardly and rearwardly and the ends 58 and 60 are received in an aperture 62 in the front of the wedge 26. The rear legs 42 and 48 extend upward and rearwardly and are provided at their upper ends with rearwardly extending substantially horizontal portions 66 and 68, respectively to leave ample clearance for the fillet 36. The length of the horizontal portions 66 and 68 required for safe clearance is not large and it has been found that a length of the order of three-fourths inch is satisfactory. The horizontal portions 66 and 68 engage the shoulder 32 and preferably engage the side walls of the box and may also engage the top 10. The cross piece 52 extends downward and engages the bottom 12 of the box. The entire keeper is thus held firmly in position within the box independently of the packing 30 so that it prevents movement of the packing without pressing or compressing the packing and transmits any forces tending to move the packing to the box instead of absorbing them.

The ends 58 and 60 on arms 54 and 56 are substantially vertical and engage in the aperture 62 in the wedge 26. From this point the arms 54 and 56 are bent at 70 and extend downwardly and forwardly to a bend 72 where they join the vertical front legs 40 and 46. The legs 40 and 46 in turn extend downwardly to a bend 74 which connects them to horizontal rearwardly extending portions 76 and 78. The horizontal portions 76 and 78 are provided with inwardly extending V bends 80 and 82 which are connected to rearwardly rising portions 84 and 86 which connect to the outer legs of the packing covering portions 48 and 50. The inner legs of the packing covering portions 48 and 50 are attached to downwardly extending portions 88 and 90 which are bent horizontally at their ends and are provided with outwardly extending V bends 92 and 94 which underlie the V bends 80 and 82. The forward ends of the V bends 92 and 94 are connected by means of clips or clamps 91 and 93 to the forward ends of V bends 80 and 82. Forward of the clips the keeper is bent downwardly at 96 to join the cross piece 52. The length of the downwardly extending portions 86, 88 and 90 are so adjusted that the upper portion 98 of the cross piece clears the underside of the journal 18 and journal collar 38.

In inserting this form of retainer, the rear legs are first positioned so that the horizontal portions 68 engage the upper rear corners of the journal box. Generally

these extensions will contact the top rear and side walls of the box. The front arms are then bent downward and backward until the ends 58 and 60 enter the opening 62 in the wedge 26. Because of the resilience of the wire, the back legs press against the back of the journal box and the ends 58 and 60 of the upright arm press resiliently against the front of the aperture 62 so that the keeper is held in place by this resilient engagement irrespective of the presence or absence of a mass of waste 39.

Resilient engagement with the journal box is also enhanced by the cross piece 52 which engages the bottom of the journal box. By proportioning the parts so that the front legs press downwardly as well as rearwardly, the cross piece 52 acts as a fulcrum urging the rear legs upwardly against the top of the box. Such downward pressure also tends to make the rear arms swing outwardly away from each other so that there is resilient engagement with the sides of the box. The retainer is thus held in position by resilient engagement with the top, bottom, sides and rear of the journal box and the opening in the bearing wedge.

The downward pressure from the upright legs and the upward pressure from the cross piece 52 is taken up by the V-shaped bends and the sole function of the clips 91 and 93 is to hold the adjacent portions of wire together. Since there is substantially no force tending to separate these two portions of wire, any stress on the clip is quite small and only a simple clip is needed. Identical clips may be used on both sides.

The retainer shown in Figures 4, 5 and 6 is also formed of a single piece of resilient wire which may be of steel, brass, or other resilient metal, and may be round, square or flat. This keeper consists generally of a front leg 100, rear leg 102 and horizontal packing coverage portion 104 on one side of the journal 18, and a front leg 106, a rear leg 108 and packing coverage portion 110 on the other side of the journal 18. A cross piece or connection 112 extends over the journal 18, preferably out of alignment with the journal collar 38, and terminates in an anchoring loop or nib 114. The front legs 100 and 106 extend upwardly and the nib 114 which is offset from the cross piece 112 by off-set 116, is received in the aperture 62 in the wedge 26. The rear legs 102 and 108 extend upwardly and may be provided at their upper ends with rearwardly extending loops 122 and 124 which engage the shoulder 32 formed by the rear wall 22. The loop portions 122 and 124 also insure that the rear legs 102 and 108 clear the fillet 36 on the journal 18. The length of the horizontal portion of the loops 122 and 124 is not large and it has been found that a length of the order of three-fourths inch is satisfactory. The upper portions of the loops 122 and 124 engage the top 10 and also preferably engage the side walls of the journal box.

The horizontal packing coverage portions 104 and 110 of the retainer terminate on their forward ends in straight horizontal portions 126 and 128 which are bent downwardly at 130 and 132 and then extend forwardly at 134 and 136. The forwardly extending portions 134 and 136 are then bent inwardly at 138 and 140 to form a pair of overlapped loops 142 and 144. The wire forming the lower portions 146 and 148 of the loops 142 and 144 is bent approximately at 134 and 136 to form forwardly extending portions 150 and 152 which support the front legs 100 and 106. The length of the downwardly extending portions 130 and 132 is so adjusted that the upper portions of the loops 142 and 144 clear the underside of the journal 18 and journal collar 38. It is to be noted that the loops 142 and 144 provide a large area of coverage to prevent the waste from shifting forwardly in the box.

Referring to Figure 6 it will be seen that the two sides of the keeper diverge from the front to the rear so that

the outer portions of the horizontal packing coverage portions 104 and 110 will resiliently and snugly engage the side walls of the box. This resilient engagement with the side wall provides an additional force to maintain the keeper in fixed position in the box.

In inserting the keeper into a journal box, the keeper is normally held with the front end raised and the rear end is slid over the top of the waste 30. When the rear end of the keeper reaches the rear of the box, the front end is pushed down to engage the nib 114 in the aperture 62 in the wedge 26 and this at the same time forces the loops 112 and 114 on the rear legs 102 and 108 upward toward the top of the box. When the retainer is properly inserted the rear legs 102 and 108 resiliently engage the side walls of the box and the loops 112 and 114 engage the shoulder 32 on the rear wall 22.

When force is applied to the nib 114 and to the lowermost point of loops 142 and 144, the loops flex upwardly placing horizontal portions 134 and 136 in torsion and rocking the upper ends of the rear legs 102 and 108 outwardly against the sides of the box. The loops 142 and 144, by the nature of their shape, are capable of providing a large amount of resilience and additional resilience is supplied through torsional twisting of horizontal portions 134 and 136. In addition, the cross piece 112 is capable of flexing at the nib 114. The resulting retainer structure may thus fit tightly into the journal box without danger of fatigue failure due to continuous flexing.

In recent years, pads have been developed to replace waste in the lubrication of journals and the retainers of the present invention are as well adapted to hold pads in position as to hold packed waste. One particularly excellent lubricating pad is described and claimed in application Serial No. 428,040 filed May 6, 1954 by John T. Hagy, now Patent No. 2,713,524. While the retainers shown in Figures 1 to 6 are adapted to hold this pad in position, by modifying the retainer as shown in Figure 7, the retainer serves as an inserting tool as well as a retainer.

The pad 154 is rectangular in shape and is so constructed as to convey lubricant to the journal 18. The pad 154 is enclosed in a bag or cover and is provided on each side with a pocket 156. The retainer shown in Figure 7 is substantially identical with the retainer shown in Figures 3 to 6 except that a horizontal leg 158 extends straight back from the lower loop portion 148 on the side of the pad 154. At its rear end, the leg 158 is provided with a loop 160 which engages in the pocket 156 to hold the pad in position. The construction of the other side of the retainer is substantially identical.

In inserting the pad, the loops of the horizontal legs are inserted in the pockets of the pad and the loops 142 and 144 cover the front face of the pad. The rear edge of the pad is inserted under the journal collar 38 and by pushing the retainer, the pad is forced into position under the journal. The nib 54 is then inserted in the opening 60 and the pad is locked in position.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A packing keeper for waste packed railway journal boxes, comprising a unitary resilient member having four upwardly extending legs, a first two of said legs including upper ends for engaging the upper rear corners of the journal box on two sides of the journal, the other two of said legs being joined by a cross brace having a single upper protrusion for anchoring said two legs in

the upper portion of the journal box, said protrusion and said upper ends forming a three point suspension for suspending the keeper in the upper portion of the journal box, a pair of horizontally extending packing engaging

5 portions attached to said first two legs for overlying the packing on both sides of the journal, and a pair of resilient loop portions connecting said other two legs and said packing engaging portions, one loop comprising a first bight connected to one of said other two legs and to the packing engaging portion adjacent to said other leg, said loops extending below said horizontally extending packing engaging portions for engaging the floor of the journal box.

10 2. A packing keeper as defined in claim 1 wherein said upper ends comprise loops lying in substantially vertical planes.

3. A packing keeper for waste packed railway journal

20 boxes, comprising a unitary resilient member having four upwardly extending legs, a first two of said legs including upper ends for engaging the roof and back of the journal box on two sides of the journal, the other two of said legs being joined by a cross brace having a single upper protrusion for anchoring said two legs in the upper portion of the journal box, a pair of horizontally extending packing engaging portions attached to said first two legs for overlying the packing on both sides of the journal, and a pair of resilient loop portions having overlapping

25 bights connecting said other two legs and said packing engaging portions, one loop comprising a first bight connected to one of said other two legs and to the packing engaging portion adjacent to said one leg, the other loop comprising a second bight connected to the other of said other two legs and to the packing engaging portion adjacent to said other leg, said loops extending below said horizontally extending packing engaging portions for engaging the floor of the journal box.

30 4. A packing keeper for waste packed railway journal

boxes, comprising a unitary resilient member having four upwardly extending legs, a first two of said legs including upper ends for engaging the roof and back of the journal box on two sides of the journal, the other two of said legs being joined by a cross brace having a single upper protrusion for anchoring said two legs in the upper portion of the journal box, a pair of horizontally extending packing engaging portions attached to said first two legs for overlying the packing on both sides of the journal, and a pair of resilient loop portions having overlapping

35 bights connecting said other two legs and said packing engaging portions, one loop comprising a first bight connected to one of said other two legs and to the packing engaging portion adjacent to said one leg, the other loop comprising a second bight connected to the other of said other two legs and to the packing engaging portion adjacent to said other leg, said loops extending below said horizontally extending packing engaging portions for engaging the floor of the journal box.

40 5. A packing keeper for waste packed railway journal

boxes, comprising a unitary resilient member having four upwardly extending legs, a first two of said legs including upper ends for engaging the roof and back of the journal box on two sides of the journal, the other two of said legs being joined by a cross brace having a single upper protrusion for anchoring said two legs in the upper portion of the journal box, a pair of horizontally extending packing engaging portions attached to said first two legs for overlying the packing on both sides of the journal, and a pair of resilient loop portions having overlapping

45 bights lying in juxtaposed substantially vertical planes and connecting said other two legs and said packing engaging portions, one loop comprising a first bight connected to one of said other two legs and to the packing

50 engaging portion adjacent to said one leg, the other loop comprising a second bight connected to the other of said other two legs and to the packing engaging portion adjacent to said other leg, said loops extending below said horizontally extending packing engaging portions for

55 engaging the floor of the journal box.

60 6. A packing keeper for waste packed railway journal

boxes, comprising a unitary resilient member having four upwardly extending legs, a first two of said legs including upper ends for engaging the roof and back of the journal box on two sides of the journal, the other two of said legs being joined by a cross brace having a single upper protrusion for anchoring said two legs in the upper portion of the journal box, a pair of horizontally extending packing engaging portions attached to said first two legs for overlying the packing on both sides of the journal, and a pair of resilient loop portions connecting said other two legs and said packing

65 engaging portions, said loop portions having overlapping

70 bights lying in juxtaposed substantially vertical planes, the lowermost portions of said bights being arranged proximate one another for contact with the lower wall of the journal box, one loop com-

prising a first bight connected to one of said other two legs and to the packing engaging portion adjacent to said one leg, the other loop comprising a second bight connected to the other of said other two legs and to the packing engaging portion adjacent to said other leg, said loops extending below said horizontally extending packing engaging portions for engaging the floor of the journal box.

6. A packing keeper for waste packed railway journal boxes, comprising a unitary resilient member having four upwardly extending legs, a first two of said legs including upper ends for engaging the roof and back of the journal box on two sides of the journal, the other two of said legs being joined by a cross brace having a single upper protrusion for anchoring said two legs in the upper portion of the journal box, a pair of horizontally extending packing engaging portions attached to said first two legs for overlying the packing on both sides of the journal, and a pair of resilient loop portions attached at one end to said other two legs and at the other end to upwardly rising off-sets carried by said packing engaging portions, one loop comprising a first bight connected to one of said other two legs and to the packing engaging portion adjacent to said one leg, the other loop comprising a second bight connected to the other of said other two legs and to the packing engaging portion adjacent to said other leg, said loops extending below said horizontally extending packing engaging portions for engaging the floor of the journal box.

7. A packing keeper for waste packed railway journal boxes, comprising a unitary resilient member having four upwardly extending legs, a first two of said legs including upper ends for engaging the roof and back of the journal box on two sides of the journal, the other two of said legs being joined by a cross brace having a single upper protrusion for anchoring said two legs in the upper portion of the journal box, a pair of horizontally extending packing engaging portions attached to said first two legs for overlying the packing on both sides of the journal, and a pair of resilient loop portions attached at one end to said other two legs and at the other end to upwardly rising off-sets carried by said packing engaging portions, said loop portions having overlapping bights whose lowermost portions are arranged proximate each other for substantially single point suspension of the keeper on the journal box floor, one loop comprising a first bight connected to one of said other two legs and to the packing engaging portion adjacent to said one leg, the other loop comprising a second bight connected to the other of said other two legs and to the packing engaging portion adjacent to said other leg, said loops extending below said horizontally extending packing engaging portions for engaging the floor of the journal box.

8. A packing keeper for waste packed railway journal boxes, comprising a unitary resilient member having four upwardly extending legs, a first two of said legs including upper ends for engaging the upper rear corners of the journal box on two sides of the journal, the other two of said legs being joined by a cross brace having a single upper protrusion for anchoring said two legs in the upper portion of the journal box, a pair of horizontally extending packing engaging portions attached to said first two legs for overlying the packing on both sides of the journal, and a pair of resilient loop portions connecting said other two legs and said packing engaging portions, said loop portions having overlapping bights whose lowermost portions are arranged proximate each other for

substantially single point suspension of the keeper on the journal box floor, said protrusion and said upper ends forming a three point suspension of the keeper in the upper portion of the journal box, one loop comprising a first bight connected to one of said other two legs and to the packing engaging portion adjacent to said one leg, the other loop comprising a second bight connected to the other of said other two legs and to the packing engaging portion adjacent to said other leg, said loops extending below said horizontally extending packing engaging portions for engaging the floor of the journal box.

9. A packing keeper for railway journal boxes comprising a pair of spaced, upwardly extending front legs, a cross brace connecting the tops of said legs, a protrusion on said cross brace for anchoring said legs in the box, a pair of substantially horizontal packing retaining portions disposed for placement on each side of the journal in the box, and a pair of resilient loops extending downwardly and inwardly so as to be disposable beneath a journal in the box, each loop being separate from each other loop and connecting a leg to the corresponding adjacent horizontal portion and being disposed for covering the front of packing located beneath the journal in the box.

10. A packing keeper for waste packed railway journal boxes, comprising a resilient member having four upwardly extending legs, a first two of said legs including upper ends for engaging the roof of the journal box on two sides of the journal, the other two of said legs meeting and terminating in upwardly extending ends for anchoring said two legs in the upper portion of the journal box, said upper ends and said nesting and inwardly extending ends forming a three point suspension for suspending the keeper in the upper portion of the journal box a pair of horizontally extending packing engaging portions each consisting of two substantially parallel legs connected to said first two legs, one of said legs of each of said packing engaging portions being connected to said other legs, the other leg of each of said packing engaging portions being connected to a cross brace extending downwardly, said parallel legs of each of said packing engaging portions having oppositely disposed substantially V-shaped overlapping portions, and a clip connecting said legs together near said overlapping portions.

11. A packing keeper for railway journal boxes, said keeper being formed of resilient wire and having a pair of connected horizontal packing coverage portions each of which has a front and rear upwardly extending leg, said rear legs having free upper ends, said front legs terminating in juxtaposition to one another, said free upper ends and said juxtaposed ends forming a three point suspension for suspending the keeper in the upper portion of the journal box, a downwardly extending cross piece attached to said packing coverage portions proximate the attachment of said front legs by means of offset portions which underlie oppositely offset portions of said packing coverage portions, and clips maintaining said overlying portions in position.
